UNITED STATES PATENT OFFICE

99,052

DESIGN FOR A PLATE OR SIMILAR ARTICLE

Viktor Schreckengost, Sebring, Ohio, assignor to The Limoges China Company, Sebring, Ohio, a corporation of Ohio

Application January 27, 1936, Serial No. 60,840

Term of patent 3½ years

To all whom it may concern:

Be it known that I, Viktor Schreckengost, a citizen of the United States, residing at Sebring, in the county of Mahoning and State of Ohio, have invented a new, original, and ornamental Design for Plates or Similar Articles, of which the following is a specification, reference being had to the accompanying drawing, forming part thereof.

The figure is a plan view of a plate, showing my new design.

I claim:

The ornamental design for a plate or similar article, as shown.

VIKTOR SCHRECKENGOST.
